UNITED STATES PATENT OFFICE.

LOUIS ROBERT KOEGEL, OF TOURS, FRANCE.

ELECTRIC HAIR-WAVING APPARATUS.

Application filed February 27, 1923. Serial No. 621,600.

To all whom it may concern:

Be it known that I, LOUIS ROBERT KOEGEL, a citizen of the French Republic, residing at Tours, Indre-et-Loire, France, have invented certain new and useful Improvements in Electric Hair-Waving Apparatus, of which the following is a specification.

This invention relates to waving apparatus for use by persons without the training 10 of a hair-dresser capable of giving quickly to the hair a wave as lasting and beautiful as that obtained slowly with ordinary curling tongs.

The frame of suitable shape is heated 15 electrically and the hair rapidly and readily wound thereon.

The heating resistance is placed inside this frame which is formed with a handle and switch for the electric current.

20 Such apparatus being compact and capable of being used anywhere where there is electricity can be readily employed when travelling without the assistance of a specialist. A specialist even if he possesses a 25 numerous clientele may reduce his staff since he can give a wave as yielding, elegant and lasting in a shorter period.

The accompanying drawing shows by way of example one type of hair waver.

30 Fig. 1 is a side view of the device partly in section.

Fig. 2 is a longitudinal section on line 2—2 of Fig. 1.

35 Fig. 3 is a section showing the application of the waving apparatus applied for producing a "permanent" wave.

The apparatus illustrated Figs. 1 and 2 consists essentially of a hollow central tube *a* of elliptical shape carrying on its sides 40 cylindrical projections *b* arranged alternately and regularly spaced.

Inside this tube *a* is housed the frame *c* of the electric resistance for heating the apparatus consisting of as many elements *d* as 45 there are projections *b*; or only one central element may be used, and the projections *b* heated by conductivity.

The tube *a* and frame *c* are mounted in a hollow handle *e* in which the terminals *f* and switch *g* are housed. The switch *g* allows the current to the heating resistance to 50 be cut off as desired.

To protect the head against burns which might occur if contact were made with the 55 apparatus the opposite end to the handle is

provided with a pad of rubber *h* or other material of poor heat conductivity.

The waver is employed in the following way:—The hair *i* is passed through an elastic band or nippers which fits a groove in 60 the rubber end *h* which is placed against the head. The hair is then wound around the central tube *a* being passed over the projections *b* alternately.

An elastic band or nippers similar to the 65 first holds the hair against the apparatus.

When this preliminary operation has been effected the switch knob *g* in the handle is moved to the "on" position. At the end of one or two minutes the heating may be cut 70 off by pressing the switch in the opposite direction or by releasing it.

The withdrawal of the hair from the apparatus is effected by removing the elastic band or nippers and unwinding it. As 75 many locks of hair as desired may be easily and readily waved so that all types of coiffure may be effected with the help of this apparatus without the requirement of any separate source of heat.

Moreover this apparatus does not make the hair "frizzy" and consequently does not render it brittle when it is being brushed.

Owing to its moderate heating this electric hair waver does not discolour fair or 85 white hair, and the wave is produced equally easily whatever the colour or texture of the hair.

To obtain a permanent wave the apparatus is arranged as shown in Fig. 3, in which 90 the resistance is placed outside of the frame *a* and the projections *b* around which is wound the lock of hair *i* to be waved. This lock is surrounded by a band saturated with a solution of borax or other suitable solvent to prevent the hair from becoming dry 95 during heating.

The waving apparatus, the length of which may be reduced or enlarged according to the length of the hair, is housed inside a copper socket *k* heated by an exterior resistance *l* and surrounded by an insulating cover *m* and a case *n* of copper or other suitable material. A diaphragm *o* similar to that employed in photographic apparatus, 100 when open allows the waving apparatus *a*, *b*, to be inserted into the socket *k*. When the diaphragm *o* is closed again and the interior temperature maintained it prevents a too rapid evaporation of the borax solution. 110

What I claim and desire to secure by Letters Patent is:—

1. An electric hair waving apparatus consisting of a hollow tube provided with projections round which the hair is wound, and an electric heater arranged inside the tube.
2. An electric hair waving apparatus consisting of a hollow tube provided with projections round which the hair is wound, an electric resistance coil arranged inside the hollow tube, a handle provided with a switch to put the resistance in circuit, and a pad of poor heat conductivity at the other end of the hollow tube.

3. An electric hair waving apparatus consisting of a hollow tube provided with projections round which the hair is wound, an electric resistance placed outside in a copper socket in which the hollow tube is arranged, means for closing said socket, an insulating covering for the socket, and a pad of poor heat conductivity at one end of the hollow tube.

In witness whereof I affix my signature.
LOUIS ROBERT KOEGEL.
